UNITED STATES PATENT OFFICE.

JAMES E. MCINTIRE, OF WEYMOUTH, MASSACHUSETTS, ASSIGNOR TO P. R. GLASS COMPANY, OF BOSTON, MASSACHUSETTS, A CORPORATION OF MASSACHUSETTS.

FOLDING-MACHINE.

1,263,449.

Specification of Letters Patent. Patented Apr. 23, 1918.

Application filed September 30, 1915. Serial No. 53,305.

To all whom it may concern:

Be it known that I, JAMES E. MCINTIRE, a citizen of the United States, and a resident of Weymouth, in the county of Norfolk and State of Massachusetts, have invented certain Improvements in Folding-Machines, of which the following description, in connection with the accompanying drawings, is a specification, like reference characters on the drawings indicating like parts in the several figures.

This invention relates to folding machines and is herein illustrated in connection with a machine for folding the margins of pieces of leather which are to be incorporated in the uppers of boots and shoes.

In folding parts of uppers of shoes such as vamps having narrow throats, the edges of the legs of which are straight or approximately so while the edges of the throats are sharply concave, a difficulty arises. Considering first a margin having a straight edge, in which case no slitting of the margin is required, the distance from the point at which the margin is initially turned up by the plow to the nearest point at which the folded over margin is forced down upon the body of the material by the presser should be sufficient to prevent stretching of the margin between these two points. If all edges were straight, or nearly so, a sufficient distance between the presser and the plow could be provided and no difficulty would be encountered. When, however, a concave curve of short radius, such as that at the throat of a vamp, is to be operated upon, the margin must be slitted to form tongues and the vamp must be swung sharply around the plow. It should be noted that when an unslitted margin is being folded, the presser, as it forces down the folded-over margin, acts to turn or pull the partially folded margin farther over, but that no such action takes place when the margin has been slitted. Instead, the tongues tend to straighten up as soon as they have passed the plow, and when the presser descends upon them they may either be pressed properly into place or they may be crumpled or bent back in the wrong direction. In the case of a slitted margin, therefore, it is desirable that the plow

should be close to the presser; and the same arrangement of parts is desirable in folding the throat of a vamp because of the sharply concave curve, so that when the vamp is swung around the plow such swinging may not move the margin out of the path of the descending presser.

Considering then the case of a vamp having two straight edges and a sharply curved narrow throat, two arrangements of the plow and the presser which are directly at variance with each other are desirable. If the distance between the point at which the margin is initially turned up and the nearest point at which the folded margin is pressed down is sufficient to prevent stretching of said margin so as to provide for proper folding of the portions of the margin having straight edges, then when the throat is reached, the margin slitted and the vamp swung sharply around the plow, the pressing will not be properly done. And on the other hand, if the distance referred to above is small enough to take care of the throat, the margin will be stretched during the folding of the portion having straight edges.

One feature of the present invention comprises a structure including a plow of such shape and so arranged as to bend each tongue downwardly just prior to the descent of the presser and at the same time to permit a concave margin of small radius of curvature, such as that of the throat of a vamp, to be swung around it. The distance between the point at which the margin is initially turned up and the nearest point at which it is forced down can thus be made sufficient to prevent stretching an unslitted margin having a straight edge; and at the same time, when a sharply concave edge is encountered and the margin is slitted, the tongues formed by the slitting are bent over just prior to the descent of the presser and the work may be swung around the plow without taking it out of the path of the presser.

Another feature of the invention relates to an improved presser foot.

These and other features of the invention including certain details of construction and combinations of parts will be described in connection with an illustrative

machines and pointed out in the appended claims.

Referring now to the accompanying drawing,—

5 Figure 1 is a perspective of the work support and operating parts of a machine which is designed particularly to fold vamps;

10 Fig. 2 is a detail showing a piece of work being slitted and folded;

Fig. 3 is a perspective of the plow;

15 Fig. 4 is a front elevation of the parts shown in Fig. 1, certain parts having been broken away or omitted to show more clearly the shape and location of the plow;

Fig. 5 is an enlarged elevation of the presser foot.

20 The feeding and folding instrumentalities of the illustrative machine are similar to those of the machine shown in the application of Glass Serial No. 5,245 filed January 30, 1915. The vamp or other piece of work is fed over a work support 1 by a feeding foot 3 which intermittently presses the work against a block 5 and moves the work forward, the block swinging on its pivot 7 and being returned to the position shown in the drawings by a spring pressed 25 plunger 9. A presser foot 11 descends intermittently upon the work between the feeding movements and has a projecting finger 111 which descends close to the side of the edge gage 13 between said gage and the knife 15. The margin of the leather, after 30 passing the knife, is turned partially over by a plow 17 which thus forms the fold, after which the fold is pressed by the presser or hammer 19. Except for the construction 35 of the plow and the presser foot the instrumentalities are substantially the same as those shown and described in the Glass application referred to above and no further description of them or the mechanism for operating them will be given.

40 The plow is peculiarly shaped in that it has a projection 117 which overhangs the body of the leather and is offset on the side next to the hammer. The shape of the plow is best shown in Figs. 3 and 4, in which it 45 will be seen that the base of the plow next to the hammer has been cut away to provide the offset effect referred to above. By making the plow of this shape it is possible to provide sufficient distance between the point 50 at which the margin is initially turned up and the nearest point at which the folded margin is pressed down so that straight unslitted margins may be folded without stretching. At the same time when a curved 55 throat is encountered and the margin slitted, the tongues are crowded over one by one by the projection 117, so as to be pressed down properly by the descending hammer, and the vamp may be swung sharply about the

60 cut-away base of the plow. Thus by locating the hammer close to a plow of this shape the two conditions of straight and concavely curved margins are provided for.

65 The plow is adjustably held in place by a screw 21 which passes through a slot 23 and is threaded into the frame of the machine. With this construction the plow may be adjusted in a direction transverse to the line of feed to provide for different curvatures 70 of the throats of vamps.

75 In machines of the present type it is desirable that the presser foot hold the leather firmly upon the support during the cutting operation; and to insure such holding the presser foot shown in the drawings has been 80 provided. This presser foot has a generally U-shaped operative end which is made resilient. When said foot is raised the position 85 of its resilient portion is indicated in Fig. 5 wherein it will be seen that the free end of the resilient U (indicated at 211) lies slightly below the plane of the bottom of the rigid portion (indicated at 311). When, therefore, the foot descends, the end 211 first contacts with the leather and then the resilient portion yields until the bottom 311 becomes operative also. This holds the leather firmly during the cutting operation and prevents improper turning or swinging of the leather.

90 Having thus described my invention, I claim as new and desire to secure by Letters Patent of the United States:

95 1. A machine of the class described, having, in combination, means for feeding a piece of stock intermittently into position to have its margin operated upon, a knife for slitting said stock to form tongues in the margin thereof, a fold presser, and a plow located between said knife and presser, 100 said plow having an overhanging portion arranged to bend each tongue downwardly and being cut away at its base on the side next to the presser to permit the throat of a vamp of small radius to be swung 105 around it.

110 2. A machine of the class described, having, in combination, means for feeding a piece of stock intermittently into position to have its margin operated upon, a knife 115 for slitting the margin, a fold presser, and a stationary plow located between said knife and presser, said plow having a projection extending over the body of the stock and offset on the side toward the presser.

120 3. A machine of the class described, having, in combination, means for feeding a piece of stock intermittently into position to have its margin operated upon, a knife for slitting the margin, a fold presser, and 125 a stationary plow located between said knife and presser, said plow being undercut at its base on the side next to the presser.

4. A machine of the class described, having, in combination, means for feeding a piece of stock intermittently into position to have its margin operated upon, means for folding the margin, means for pressing the fold, a knife for slitting said margin, an edge gage, and a presser foot having a sub-

stantially U-shaped resilient operative portion, there being formed at the free end of the U a finger adapted to descend between 10 the knife and the edge gage.

In testimony whereof I have signed my name to this specification.

JAMES E. McINTIRE.
